UNITED STATES PATENT OFFICE.

DAVID W. HAWKSWORTH, OF BIRMINGHAM, MICHIGAN, ASSIGNOR, BY MESNE ASSIGNMENTS, TO HUTCHINS CAR ROOFING COMPANY, OF DETROIT, MICHIGAN, A CORPORATION OF DELAWARE.

CAR ROOF.

Application filed October 19, 1925. Serial No. 63,433.

This invention relates to car roofs and particularly to all-metal car roofs of that type in which the carlines are arranged above the roofing sheets and form the supports and weatherproofing caps therefor.

The invention has among its objects to improve generally this particular type of car roofs and further relates to a simplified and improved construction of running board saddle and to a roof sheet fastening means designed to be also employed as a fastening means for the running board saddle.

Various other objects, advantages and novel details of construction of the invention will be made more apparent as this description proceeds, especially when considered in connection with the accompanying drawings, wherein

Fig. 1 is a fragmentary transverse sectional elevational view of a car roof constructed in accordance with my invention,

Fig. 2 is a top plan view of the structure illustrated in Fig. 1,

Fig. 3 is a fragmentary side elevational view of a car roof constructed in accordance with this invention,

Fig. 4 is an enlarged detailed sectional view taken substantially on the plane indicated by line 4-4 in Fig. 1, and

Fig. 5 is a similar sectional view taken substantially on the plane indicated by line 5-5 in Fig. 1.

Referring now particularly to the drawings wherein like reference characters indicate like parts, it will be noted that there is illustrated carlines 10 of inverted U-shape in cross section provided with side flanges 11 and side plates 12 of Z cross section, the carlines being turned down over the side plates and having their ends secured thereto by means of rivets or the like 13 passing preferably through the ends of the side flanges 11. In the construction herein shown spacing washers 14 are arranged between the upstanding flange of the side plate 12 and the flanges 11 of the carline.

The roof sheets 15 are provided with upwardly offset returnbent side edges 16, the roof sheets being mounted upon the car with the edges 16 thereof arranged in overlapping relation, as clearly shown in Figs. 4 and 5. The overlapping edges 16 of adjacent roof sheets extend up within the adjacent carline 10 and are enveloped thereby.

In practice a non-metallic washer 17, preferably of impregnated felt or canvas, is interposed between the roofing sheets 15 and the carline 10 in the manner clearly illustrated in Figs. 4 and 5. Consequently this washer in connection with the carline 10 weatherproofs the joint between the adjacent roof sheets.

For supporting the roof sheets within the carline there is provided a plurality of spaced sheet fastening members 18 in the form of shoulder bolts, each having an enlarged shoulder portion 19 arranged between the overlapping edges of the roof sheets 15 and the under side of the crest of the carline to thereby space the overlapping roof sheets from the crest of the carline. The upper end of each shoulder bolt is riveted over as at 20 and consequently the opening in the carline through which the bolt passes is weather proofed. Associated with each bolt 19 is a sheet supporting bar 21 held in place by nut 22 threaded on the lower end of the bolt. A lock washer 23 is preferably interposed between the sheet supporting bar 21 and the nut 22.

The running board saddles 24 are attached directly to the carlines and each saddle comprises a flat horizontal portion 25 and a portion 26 engaging the crest of the carline and preferably correspondingly shaped so as to effect a positive engagement therewith. The running boards 27 rest upon the horizontal portions 25 of the saddle and are secured thereto by bolts 28 passing through the boards and through suitable apertures arranged in the saddle. As shown by dotted lines in Fig. 5 the saddles 24 arranged at the splicing points of the running board may have the horizontal portion 25 duplicated as indicated at 25'.

For simplifying and cheapening the cost of construction and assembly the running board saddles 24 are preferably secured in place upon the carlines 10 by certain of the sheet supporting shoulder bolts 18 and therefore, as shown in Fig. 5, the upper ends of the shoulder bolts 18 at the points where the running board saddles 24 are located, are extended upwardly through aligned openings in the running board saddle and the heads 20 thereof riveted over so as to rigidly connect the running board saddles to the carlines at the crests thereof.

From the foregoing it will be apparent that the present invention offers a simple and cheap means of efficiently connecting the roof sheets to the carlines and of likewise connecting the running board saddles thereto without a duplication of fastening means. Furthermore, the assembly of the roof is facilitated because the sheet fastening means are previously fixed by riveting to the carlines as shown the shouldered portions of the shoulder bolts employed in the present invention affording positive means for spacing the overlapping ends of the roofing sheets from the crest of the carlines and positioning the nuts of these bolts sufficiently near the plane of the under side of the roof to enable them to be conveniently tightened.

While an embodiment of the invention is illustrated and described somewhat in detail, it will be readily apparent that various changes in the specific form illustrated may be resorted to without departing from the spirit and scope of the invention and to this end reservation is made to make such changes as may come within the purview of the accompanying claims.

What I claim as my invention is:

1. In a car roof, the combination with carlines of inverted U-form having shoulder bolts riveted thereto, of roof sheets extending up within the carlines into engagement with said shoulders, and means carried by said bolts for fastening the sheets thereto.
2. In a car roof, the combination with carlines of inverted U-form, of roof sheets having overlapping upwardly offset side edges enveloped by the carlines, and shoulder bolts riveted to said carlines, the said bolts having their shoulders engaging the edges of the sheets within the carlines.
3. In a car roof, the combination with a carline of inverted U-form, a running board saddle, and roofing sheets extending up within the carline, of shoulder bolts riveted to said carline, with one thereof riveted also through said saddle, said bolts projecting within said carline and means on said bolts cooperating with said shoulders for clamping the roofing sheets to said carline.
4. In a car roof, the combination with a carline of inverted U-form, and roof sheets extending up within the carline, of a sheet fastening means comprising a shoulder bolt riveted to the crest of the carline with the

shoulder thereof spacing the sheets from said carline. 55

5. In a car roof, a carline of inverted U-form, roof sheets having overlapping edges extending up within said carline and sheet fastening means comprising a shoulder bolt 60 secured to said carline with the shoulder thereof arranged between said carline and sheet edges for spacing the latter.

6. In a car roof, a carline of inverted U-shape, shoulder bolts riveted to said carline and extending within the same, roof sheets provided with overlapping upwardly offset edges extending within said carline and means on said bolts for clamping said roof sheets against the shoulders of said bolts. 65 70

7. In a car roof, a carline of inverted U-form, roof sheets having overlapping upwardly offset edges extending upwardly within said carline, shoulder bolts riveted to said carline and extending through said 75 overlapping sheet edges and means on said bolts for clamping said sheet edges against the shoulders of said bolts.

8. In a car roof, a carline of inverted U-form, roofing sheets having overlapping upwardly offset edges extending upwardly within said carline, and a bolt extending through the carline and the edges of the roofing sheets, the said bolt being provided with an enlarged shoulder portion intermediate its ends, one end of the said enlarged portion bearing against the underside of the said carline and the other end of the said enlarged portion bearing against the said roofing sheets. 80 85 90

9. In a car roof, a carline of inverted U-form, roof sheets having overlapping upwardly offset edges extending upwardly within said carline, a bolt extending through the said carline and the said roofing sheets, the said bolt having an enlarged portion intermediate its ends for spacing the said roof sheets from the said carline, the said enlarged portion forming oppositely facing shoulders on the bolt, means formed on one end of the bolt for clamping the carline against one of the shoulders and means carried by the other end of the bolt for clamping the roof sheets against the other of the said shoulders. 95 100 105

In testimony whereof I affix my signature.

DAVID W. HAWKSWORTH.
